FOLDING COUCH.

1,281,333.

Specification of Letters Patent. Patented Oct. 15, 1918.

Application filed March 16, 1917. Serial No. 155,221.

To all whom it may concern:

Be it known that I, WILLIAM E. FRANK, a citizen of the United States, residing at St. Louis, Missouri, have invented a certain new and useful Improvement in Folding Couches, of which the following is a full, clear, and exact description, such as will enable others skilled in the art to which it appertains to make and use the same.

10 This invention relates to couches, davenport's and similar articles of furniture that are provided with a foldable mattress frame that can be opened or extended when it is desired to convert the device into a bed.

15 One object of my present invention is to provide a folding couch, davenport or similar article of simple construction that can be opened and closed easily.

Another object is to provide a device of 20 the character referred to that is equipped with springs which are so arranged that they assist in the operation of opening the mattress frame or closing said frame and also absorb the shock on the mattress frame 25 when it is moving into its final closed position.

Another object is to provide a folding couch, davenport or similar article of novel construction in which ample room is provided for the mattress and bedding when 30 the couch is in its closed position.

And still another object is to provide a folding couch, davenport or similar article that is equipped with a three-piece mattress 35 frame, a seat and a back that is combined with said seat and frame in such a manner that it serves as a brace for the end section of the mattress frame when said frame is extended or opened. Other objects and de- 40 sirable features of my invention will be hereinafter pointed out.

Figure 1 of the drawings is an end view, partly in elevation and vertical section, of a folding couch constructed in accordance 45 with my invention, showing the couch open.

Fig. 2 is a top plan view of same.

Fig. 3 is a vertical transverse sectional view, showing the couch closed; and

Fig. 4 is a detail sectional view, taken 50 on the line 4-4 of Fig. 3.

Referring to the drawings, which illustrate the preferred form of my invention, A designates the end frames of my im-

proved couch, which may be of any preferred construction and design, and 1 and 2 55 designate cross members that connect said end frames together, the cross member 2 serving as an auxiliary stop or support for the upper edge of the back B of the couch when the couch is closed, as shown in Fig. 3. 60 The mattress frame of the couch herein shown is formed in three sections, consisting of a rear section C of substantially U shape in outline, an intermediate section D and a front section E which is also sub- 65 stantially U-shaped in outline, as shown in Fig. 2, said sections having combined therewith a mattress-supporting structure formed either from a woven wire fabric or a link and coil spring structure. Said sections are 70 pivotally connected together and are combined with the end frames A in such a manner that when the couch is closed, as shown in Fig. 3, the intermediate section D will lie above the rear section C and the front sec- 75 tion E will stand in a position at substantially right angles to the intermediate section D behind the back B of the couch. The seat F of the couch is connected by means of links 3 and 4 to the intermediate section 80 D of the mattress frame in such a manner that when the couch is closed said seat will lie above the intermediate section D of the mattress frame, and when the couch is open, as shown in Fig. 1, said seat will occupy a 85 horizontal position some distance beneath the mattress frame. The frame 5 which carries the upholstered portion of the back B is pivotally connected at its lower edge to the seat frame 7 and is also pivotally 90 connected at 8 to the front section E of the mattress frame in such a manner that when the couch is closed the back B will occupy an inclined position at the rear of the seat, and when the couch is open, as shown in 95 Fig. 1, said back will constitute an inclined brace that supports the free end of the front section E of the mattress frame and holds it in horizontal alinement with the intermediate section of the mattress frame. It is 100 immaterial, so far as my broad idea is concerned, how the various sections of the mattress frame are formed, but I prefer to form said sections from pieces of angle iron, the intermediate section D of the frame merely 105 consisting of two side members 9 that are

pivots 11 that connect the intermediate section and rear section of the mattress frame together. As shown in Fig. 4, the side pieces of said rear section C of the mattress frame lie between the end frames A and the vertical webs of the supporting brackets 16, and the side members 9 that

5 pivotally connected at 10 to the side pieces of the front section E and pivotally connected at 11 to the rear section C of the mattress frame.

10 In order to provide ample space for the mattress and the bedding between the rear section C and the intermediate section D of the mattress frame when the couch is closed, said rear section C is connected to the end frames A in such a manner that the rear end of same will drop downwardly automatically when the mattress frame is moved into its closed position and will move upwardly automatically into a horizontal position when said mattress frame is opened or extended. In the form of my invention herein shown this is effected by pivotally connecting the front ends of the side pieces of said rear section C to the end frames, and connecting the rear end portion of said section C to the end frames by two pairs of toggle links 12, which, in turn, are joined by means of rods 13 to the intermediate section D of the mattress frame. The rods 13 are provided with upturned ends 14 which are pivotally connected at 14^a to the side members 9 that constitute the intermediate section D of the mattress frame at a point in advance of the pivotal connection between the sections C and D of the mattress frame when said frame is extended. Consequently, when the intermediate section D is swung upwardly and rearwardly during the operation of closing the mattress frame, the links 13 will also move rearwardly and break or collapse the toggles 12, thus permitting the rear end portion of the section C of the mattress frame to swing downwardly into the position shown in Fig. 3. When the intermediate section C of the mattress frame is swung upwardly or forwardly during the operation of opening or extending the mattress frame, the links 13 will also move forwardly, and consequently, straighten the toggles 12, thereby moving the rear end portion of the section C upwardly into a horizontal position, as shown in Fig. 1. The end frames A of the couch are provided with stops or supports 15 on which the rear section C of the mattress frame rests when the couch is closed, and while it is immaterial, so far as my broad idea is concerned, how the rear section C of the mattress frame is pivotally connected to the end frames A, I prefer to provide the end frames with supporting brackets or plates 16 of the form shown in Fig. 4, to which the side pieces of said rear section C are pivotally connected by the same pivots 11 that connect the intermediate section and rear section of the mattress frame together. As shown in Fig. 4, the side pieces of the rear section C of the mattress frame lie between the end frames A and the vertical webs of the supporting brackets 16, and the side members 9 that

constitute the intermediate section of the mattress frame lie on the opposite sides of said webs.

The links 4 that connect the seat F to the intermediate section D of the mattress frame are provided with legs or extensions 4^a that rest on the floor when the mattress frame is in its open position, and thus form rigid supports for the intermediate part of the mattress frame. At such times the rear part of the mattress frame is supported firmly by the end frames A and by the toggle links 12, and the front portion of said mattress frame is supported by the back B, as previously described.

In order to hold the supporting legs 4^a rigid and in a perpendicular position when the couch is open, I connect the front edge of the seat F to the end frames by means of links 17 that are pivotally connected at 17^a to the end frames and at 17^b to the seat frame 7, said links 17 also being utilized to carry a rigid member 18 that forms a continuation of the front edge of the seat F when the couch is closed, and thus hides the space under the seat between the end frames. The rear section C of the mattress frame is provided with stops 19 on which the intermediate section D of the mattress frame rests when the couch is closed, and if desired, the top cross piece 2 that serves as an auxiliary support for the upper edge of the back B may be provided with a catch 20 that co-operates with a catch device 21 on a rigid member 22 that extends longitudinally of the back at the upper edge of same, so as to lock the couch in its closed position. As previously stated, one of the novel features of my improved couch is that it is equipped with springs which are so arranged that they assist in the operation of opening and closing the mattress frame and also absorb the shock on said frame when it is moving to its final closed position. In the form of my invention herein shown two contractile springs 23 are employed for this purpose, which springs are connected at their rear ends to the cross member of the rear section C of the mattress frame and at their front ends to rods 24 which are mounted in bearings 25 on the side members 9 of the intermediate section D of the mattress frame in such a manner that when the couch is open, said rods will extend substantially parallel to said side members 9, and when the couch is closed, said rods will stand in a position at substantially right angles to the side members 9. As shown in Fig. 2, each of the rods 24 is provided at its front end with a laterally-projecting arm 24^a that is journaled in its co-operating bearing 25, and the arm on each of said rods is provided with an upwardly-projecting portion or extension 24^b that is arranged at substantially right angles to the horizontal flange of the side

member 9 on which the bearing 25 is mounted. The springs 23 and rods 24 are so arranged that when the couch is in its open position, as shown in Fig. 1, said rods will 5 lie below the pivots 11 which join the intermediate section and rear section of the mattress frame to the end frames, thereby causing the springs to exert pressure on the intermediate section of the mattress frame in 10 a direction tending to swing said section downwardly, and consequently, overcoming any tendency of the mattress frame to close accidentally. When it is desired to close the couch the user merely pushes the back 15 B or the front section of the mattress frame upwardly and rearwardly, thereby causing the intermediate section of the mattress frame to swing upwardly on the pivots 11. As soon as the links 24 cross the pivots 11, 20 or, in other words, become positioned above said pivots, due, of course, to the upward swinging movement of the intermediate section D, the springs 23 will exert a rearward pull on said intermediate section, or a 25 pull in a direction tending to cause said intermediate section to move into its closed position. When the intermediate section swings upwardly and rearwardly, the front section E of the mattress frame, the seat F 30 and the back B will fold automatically into the position shown in Fig. 3, owing to the manner in which said parts are connected together and to the manner in which the front edge of the seat is joined to 35 the end frames. During the first part of the upward and rearward movement of the intermediate section of the mattress frame the arms 24^a on the rods 24 to which the springs are connected merely turn 40 in the bearings 25, but when the side members 9 on which said bearings are mounted reach such a position that the horizontal flanges on said members 9 strike against the upturned extensions 24^b on the arms 45 24^a, or, in other words, a position at substantially right angles to said rods, the rods 24 will start to move with the members 9 and will finally reach such a position that they exert a forward pull on the springs 23, 50 thereby causing said springs to absorb the shock on the intermediate section of the mattress frame when it is moving into its final closed position.

If desired, the front section E of the mattress frame can be provided with auxiliary 55 supporting legs 26 that can be swung downwardly into engagement with the floor, as shown in broken lines in Fig. 1, so as to assist the back B in supporting the front portion of the mattress frame. In the couch herein shown each of the auxiliary supporting legs 26 is formed from a piece of rod 60 bent into substantially V form and provided at its upper end with eyes or hooks 27 that 65 pass through holes in the side flanges of the

front section E of the mattress frame, said auxiliary legs being so arranged that they can be snapped into engagement with clips 28 on the cross piece of the front section E, so as to securely hold the bedding and the 70 mattress in operative position on the mattress frame when the couch is closed.

While I have herein illustrated my invention embodied in a folding couch or davenport of the type in which the mattress frame 75 comprises three sections that can be opened, so as to form a bed in which the occupant lies at substantially right angles to the length of the couch, I wish it to be understood that the invention is also applicable 80 to folding couches and davenports of the type commonly termed "day beds", in which the mattress frame is composed of two sections, each of which is of substantially the same length as an ordinary bed spring and 85 one-half the width of same.

A folding couch or davenport of the construction herein illustrated and described can be opened and closed easily, on account 90 of the fact that it is provided with springs that are normally under tension and in readiness to assist the user in the operation of closing or opening the couch. Furthermore, said springs are so arranged that when the couch is being closed the springs 95 effectively absorb the shock on the collapsible mattress frame when it is moving into its final closed position. In addition to the functions above mentioned, the springs also overcome any tendency of the mattress 100 frame to close accidentally when the couch is being used as a bed. My improved couch is of such simple construction that it can be manufactured at a low cost; is not liable to get out of order when in use and the parts 105 of same are so designed and arranged that ample space is provided for the mattress and the bedding when the couch is closed. In addition to the desirable features above pointed out, my improved couch presents 110 a neat and ornamental appearance.

Having thus described my invention, what I claim, and desire to secure by Letters Patent, is:

1. A couch, davenport or similar article 115 provided with a foldable mattress frame that comprises a hinged section which can be turned over, a contractile spring, and a link interposed between said spring and hinged section of said frame and mounted 120 on said section in such a manner that it will move into a position at an angle to the longitudinal axis of the spring so as to place said spring under tension before said hinged section reaches its final closed position, thereby causing said spring to absorb 125 the closing shock on said hinged section.

2. A couch, davenport or similar article provided with a foldable mattress frame 130 that comprises a hinged section which can

be turned over, a contractile spring, a link joined to said spring and to the hinged section of said frame in such a manner that it lies below the pivot of said section when the mattress frame is open, and means for causing said link to assume such a position that it places said spring under tension before said hinged section reaches its final closed position, thereby causing the closing 10 shock on said hinged section to be absorbed.

3. A couch, davenport or similar article provided with a foldable mattress frame, comprising a hinged section that can be turned over, a contractile spring and a link joined to said hinged section in such a manner that they are arranged in substantially axial alinement with each other when the mattress frame is open, and means for causing said link to assume an angular position 15 with relation to said spring during the operation of closing the mattress frame so that said spring will absorb the closing shock on said hinged section.

4. A couch, davenport or similar article provided with a foldable mattress frame that comprises a hinged section which can be turned over, a contractile spring, a link connected to said spring and journaled in a bearing on said hinged section, said spring 25 and link being so arranged that the spring exerts a pull on said hinged section in a direction tending to close it during the first part of the operation of closing the mattress frame, and means for causing said link to 30 move with said hinged section and place said spring under tension during the last part of the operation of closing the mattress frame.

5. A couch, davenport or similar article provided with a foldable mattress frame that comprises a hinged section which can be turned over, a bearing on said hinged section, a link journaled in said bearing, a contractile spring connected to said link, and a 40 coöperating means on said link and hinged section for preventing the link from turning in said bearing during the last part of the operation of closing the mattress frame; for the purpose described.

50 6. A couch, davenport or similar article provided with end frames, a foldable mattress frame that comprises a rear section and a pivotally mounted section that lies above same when the mattress frame is closed, both 55 of said sections being pivotally connected to the end frames so as to swing on the same axis, toggle links for supporting the free end of said rear section, and a connection between said toggle links and said pivotally 60 mounted section for straightening the toggle when the mattress frame is opened and for breaking the toggle when said frame is being closed.

7. A couch, davenport or similar article, 65 comprising end frames, a foldable mattress

frame comprising a rear section pivotally connected at its front end to the end frames, a pivotally mounted section that lies above said rear section when the mattress frame is closed, a collapsible means for supporting 70 the rear edge of said rear section, stops on said end frames on which said rear section rests when the mattress frame is closed, and upwardly-projecting portions on said rear section on which said pivotally mounted 75 section rests when the mattress frame is closed.

8. A couch, davenport or similar article provided with a three-piece mattress frame that can be opened and closed, and a seat 80 and back combined with said mattress frame in such a manner that the seat lies under the intermediate portion of the mattress frame and the back extends upwardly from said seat to the front section of the frame so as 85 to support said section when said frame is in its open position.

9. A couch, davenport or similar article provided with a jointed mattress frame, a seat connected to said frame by links in 90 such a manner that it lies underneath said frame when said frame is in its open position, and a back pivotally connected at its lower edge to the normally rear edge of said seat and at its upper edge to the front portion of said frame in such a manner that it 95 serves as an inclined supporting brace for the front end of said frame.

10. A couch, davenport or similar article provided with a collapsible frame which 100 comprises a section which can be turned over, end frames to which said section is pivotally connected, supporting legs for said section pivotally connected to the ends of same, a seat pivotally connected at its ends 105 to said legs, and links pivotally connected to said end frames and to said seat for holding the seat in a certain position when the couch is open.

11. A couch, davenport or similar article 110 provided with end frames, a foldable mattress frame comprising a rear section, an intermediate section and a front section pivotally connected together, a pivotal connection between said end frames and said rear section, a collapsible means for supporting the rear end of said rear section, a seat connected to said intermediate section by means of links, and a back pivotally connected to said seat and to the front section of said 115 mattress frame.

12. A couch, davenport or similar article provided with end frames, a foldable mattress frame comprising a rear section, an intermediate section and a front section pivotally connected together, a pivotal connection between said end frames and said rear section, a collapsible means for supporting the rear end of said rear section, a seat connected to said intermediate section by means 120 125 130

of links, a back pivotally connected to said seat and to the front section of said mattress frame, legs for supporting the mattress frame when it is extended, contractile springs, links joined to said springs and to the intermediate section of said frame in such a manner that they lie below the piv-

ots of said section when the frame is open, and means for causing said links to assume such a position when the frame is being closed that said springs will be placed under sufficient tension to absorb the closing shock on the sections of said frame.

WILLIAM E. FRANK.
